UNITED STATES PATENT OFFICE

EDMUND L. DAY, OF WESTLINE, PENNSYLVANIA

PROCESS FOR TREATING VAPOR OF WOOD OR ITS BY-PRODUCTS

Application filed December 17, 1928. Serial No. 326,591.

This invention relates to a process for treating the vapor produced by the destructive distillation of wood or its by-products such as wood tar and wood oils, and has for one of its objects to provide a process which shall be capable of being practiced in a manner to produce a distillate containing comparatively little foreign matter.

To attain this and other objects the invention comprehends treating the vapor within the apparatus in which it is generated and in a manner to effect the precipitation of its heavier or high boiling point components and thereafter condensing the thus purified vapor.

The invention also comprehends the partial fractionation of the vapor within the retort of the apparatus so as to permit the precipitated components to be subjected to further distillation.

The invention also comprehends the further fractionation of the vapor in the column of the apparatus and the conveying of certain of the precipitated components into the retort for further distillation.

The invention also comprehends the carrying of the vapor through a circuitous path arranged within the column and provided with relatively spaced fractionating units.

The invention also comprehends the fractionation of the vapor by divided material, spirals, broken brick, vitrified clay objects, charcoal or the like.

The invention also comprehends subjecting the vapor to the action of fractionating units as it passes through horizontal and vertical chambers within the column, and regulating the temperature of the horizontal chambers.

The invention also comprehends subjecting the vapor to the action of fractionating units as it passes through a circuitous path within the column and provided with a discharge opening below its highest point.

The process is hereinafter more fully described and claimed, and a preferred form of apparatus for practicing the process is shown in the accompanying drawing, wherein:

The single figure is a sectional view taken

on the plan extending vertically and centrally through the apparatus.

The apparatus comprises a retort 1 which is supported within the combustion chamber of a furnace 3. The retort 1 is provided with front and rear doors 4 and 5, respectively, which are removably secured in place by elements 6 and rendered vapor tight by the gaskets 7. The retort 1 comprises a chamber 1^a for the reception of wheel supported trucks 8 carrying the material to be treated, and a chamber 1^b for the reception of a wheel supported fractionating unit 9 which is in the form of a cartridge. The trucks 8 and the cartridge 9 are mounted upon rails 10 which extend through and beyond the retort 1. The rails 10 are provided immediately adjacent the ends of the retort 1 with hinged removable sections 11 which are adapted to be raised into their solid line position in order to permit the application or removal of the doors 4 and 5 and which are adapted to be lowered into their dotted line position when the doors are removed in order to permit the trucks 8 and the cartridge 9 to be moved into or withdrawn from the retort 1.

The cartridge 9 comprises a casing 12 which is fully open at its top side. The casing 12 is provided at its lower side with an inlet passage 13 which extends from the front to the rear side of the casing and embodies imperforate top and bottom walls 14 and 14^a, and perforated side walls 15. The inlet passage 13 is fully open at its front end, and the rear end thereof is closed by a hinged clean out door 16. The casing 12 is mounted upon beams 17 which are supported to the axles 18 of flanged wheels 19 resting upon the rails 10. Flanges 20 and 21 secured to the retort 1 and to the front side of the casing 12, respectively, a packing strip 22 arranged between the flanges, a plate 22^a provided with a packing strip 22^b, and packing material 23, such as sand or the like, arranged upon the bottom of the retort, function to seal the cartridge 9 within its compartment 1^b in such manner that all the vapor generated in the compartment 1^a will pass into the passage 13 and upwardly throughout every part of the car-

tridge on its way to the outlet 1° of the retort 1.

A screw 24 carried by the rear door 4 and bearing against the rear side of the cartridge 9 permits the gasket 22 and packing strip 22^b to be placed under the pressure necessary to establish a vapor proof connection between the flanges 20 and 21 and between the cartridge and the plate 22^a.

10 The cartridge 1 also comprises fractionating material 25 which is arranged within the casing 12 and may consist of any suitable divided substance such as broken brick, terra cotta material, baked clay or vitrified spirals 15 such as are commonly used in acid distillation, marbles, charcoal, saw dust or other material screens or the like. The cartridge 9 is provided with a receptacle 25^a which is arranged therein directly below the outlet 1°.

20 A column 26 of substantially T-form and presenting a vertical member 27 and a horizontal member 28, is arranged above the retort with the lower end of its vertical member in communication with the outlet 1° of 25 the retort. The column member 28 communicates with the column member 27 below the horizontal center of the latter. A horizontal partition 29 is fixed within the column member 27 in substantial alignment with the 30 horizontal center of the column member 28.

35 A partition 30 is supported within the column member 28 approximately at said center, and has its inner end resting upon the partition 29 and its outer end spaced from the outer end of this column member. The partition 29 separates the column member 27 into upper and lower vertical chambers, and the partition 30 separates the column member 28 into upper and lower horizontal chambers which communicate with each other at their outer ends and have their inner ends arranged in communication with the upper and lower vertical chambers, respectively. The partition 29 is provided with an opening 40 31, and secured to the under side thereof is a trap 32. A pipe 33 extends from the trap 32 to a point beyond the column member 27, and is provided with a drain cock 34 which extends into a trap 35. The column member 50 28 is provided in its lower side with a drain opening 36, and is provided inwardly of said opening and below the partition 30 with a dam 37. A trap 38 is secured to the lower side of the column member 28 below the drain opening 31, and is provided with a drain cock 39.

55 The lower chamber of the column member 27 is provided with a fractionating unit 40, and the upper chamber of this column member is provided with a fractionating unit 41. These fractionating units are supported by the grates 42 and 43, respectively, and they may consist of any of the materials hereinbefore referred to. The upper and lower chambers of the column member 28 are provided

with a fractionating unit 44. This unit is arranged in the outer communicating ends of the chambers and above and below the partition 30, and it preferably consists of charcoal.

70 The upper chamber of the column member 27 is provided with a down flow discharge passage 45 which communicates at its upper end with the upper end of this chamber and which communicates at its lower end with the discharge opening 46 to which the condenser or a plurality of condensers in series, not shown, are connected.

75 The upper end of the column member 27 is closed by a door 46 which is hinged, as at 47, and is secured in closed position by a key 48 which will fracture under a pressure that would tend to disrupt the column 26. The door 46 is counterbalanced by a weight 49 which is connected thereto by a cable 50 passing over direction pulleys 51. As it is secured in closed position by a breakable pin 48, and as it is counterbalanced, the door 26 will open whenever the pressure within the column 26 becomes so high as to render the destruction of the column impossible. The outer end of the column member 28 is closed by a door 52 which is hinged as at 53, and secured in closed position by elements 54 which may be of the 80 type easily broken so as to provide a second 95 safety door.

85 To maintain the column member 28 at the required temperature during the initial phase of the operation of the process, a gas or oil burner 55 of any well known or appropriate 100 construction is employed. This temperature increasing means may, if desired, take the form of a small furnace or electric heater. Means for maintaining the temperature of the column member 28 at the required degree 105 after the initial phase of the operation of the process, may consist of a water bath or of a blower 56 provided with a driving pulley 56^a, a manifold 57 surrounding the outer end of the column member and receiving air from the blower, and nozzles 58 communicating with the manifold and surrounding the column member. If desired, the blower 56 may be driven directly by an electric motor. The column member 27 is provided with a water jacket 60 having an intake pipe 61 and a discharge pipe 62 and constituting means for maintaining the temperature of this column member at the required degree after the 110 initial phase of the operation of the process. This column member is provided with a pyrometer 63, and it is maintained at a temperature substantially equal to the boiling point 115 of acetic acid. The down-flow discharge passage 45 is provided at its lower end with a tar discharge port 64 which communicates with a trap 65 having a drain cock 66. The column member 28 is provided with a pyrometer 59, and it is maintained at a temperature sub-

120 125 130

stantially equal to the boiling point of crude wood tar.

As this apparatus constitutes the subject matter of my copending application, filed the 17th day of December, 1928, Ser. No. 326,590, a further description thereof is deemed unnecessary. Attention is directed to my application filed December 17, 1928, Ser. No. 326,592.

10 In practice, the fractionating unit 9 is placed and sealed within the retort 1^b, the trucks 8 bearing the wood to be treated are moved into the retort chamber 1^a, and the doors 4 and 5 are closed and sealed. The apparatus 15 is worked under a slight vacuum. The vapor generated in the retort chamber 1^a flows through the fractionating unit 9, then through the fractionating unit 40, then through the fractionating unit 44, then 20 through the fractionating unit 41, and thence downwardly through the outlet passage 45 into the condenser. The components separated from the vapor by the fractionating unit 9 remain in the retort chamber 1^b for 25 further distillation. The components separated from the vapor by the fractionating unit 40 are precipitated into the receptacle 25^a for further distillation. If desired, this receptacle may be omitted and these components 30 permitted to fall onto the fractionating material 25. The components separated from the vapor by the fractionating unit 44 will remain in the lower chamber of the column member 28 and be subjected to further 35 distillation. The tar accumulating in the traps 35, 38 and 65 may be withdrawn by opening the cocks 34, 39 and 66.

It will be seen that the vapor flows through 40 a vapor tight apparatus, that it is progressively fractionated at progressively lower temperatures, and that its fractionation is materially facilitated by causing it to flow through a circuitous path, in which three of the fractionating units are arranged and 45 which extend from the retort to the condenser, and by the means which permits said path to be maintained at the required temperatures. The distillate or acetic acid produced by this 50 process will contain such a small amount of foreign matter as to require comparatively little refining.

In carrying out my process in actual practice, I use wood for the purpose of distillation and immediately extract in the first instance, the acids or break up the component parts without extracting the ordinary tars and oils in any great amount, thereby eliminating the step which has ordinarily followed 55 in first extracting the tars and oils.

In following out my process, I may however, use tar or heavy oils for the purpose of distillation, substituting the tar and oils for the woods and then proceed to break up this 60 tar or oil into acid or its component parts.

In following my process, the resultant products would be acetic acid, wood pitch, and heavy creosote oil. I do not get light oils.

What I claim is:

A process for the distilling of wood and treating its by-products, consisting of heating the wood and driving off vapor, passing the vapor through a closed circuitous substantially horizontal path of material length, 75 positively varying the temperature of the vapor in its passage through the closed circuitous path by a controlled heating and cooling means, for fractionating the vapor, then passing the vapor in a vertical direction and then further fractionating the vapor 80 while conveying the vapor in a downward direction.

In testimony whereof I affix my signature.
